DESIGN FOR A COMBINATION KITCHEN TOOL

Ada Deerf, Brooklyn, N. Y.

Application December 29, 1939, Serial No. 89,216

Term of patent 7 years

To all whom it may concern:

Be it known that I, Ada Deerf, a citizen of Poland, residing at Brooklyn, county of Kings, and State of New York, have invented a new, original and ornamental Design for a Combination Kitchen Tool, of which the following is a specification, reference being had to the accompanying drawing, forming a part thereof.

In the drawing:

I claim:

The ornamental design for a combination kitchen tool, as shown.

ADA DEERF.
